Patented June 29, 1971

220,996

COMBINED TOY DOLL AND TEA SET DISPLAY PACKAGE

Richard W. Irons, Torrance, Frank A. Mediate, Pasadena, and Thomas E. See, Huntington Beach, Calif., assignors to Mattel, Inc., Hawthorne, Calif.

Filed Feb. 9, 1970, Ser. No. 21,342

Term of patent 14 years

Int. Cl. D9—04

U.S. Cl. D9—193

FIG. 1

FIG. 2

FIG. 3

FIG. 4

FIG. 5

FIG. 1 is a front perspective view of a combined toy doll and tea set display package embodying our new design;

FIG. 2 is a top plan view thereof;

FIG. 3 is a rear view thereof;

FIG. 4 is a right side view thereof; and

FIG. 5 is a bottom view thereof.

We claim:

The ornamental design for a combined toy doll and tea set display package, as shown.
